(57) **CLAIM**

The ornamental design for a hygiene implements holder with shield, as shown and described.

DESCRIPTION

FIG. 1 is a top front right side perspective view of a hygiene implements holder with shield having the cover in an open position;

FIG. 2 is a bottom rear left side perspective view of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 1;

FIG. 9 is a top front right side perspective view of FIG. 1 and having the cover in a closed position;

FIG. 10 is a top front left side perspective view of FIG. 1 having a manual toothbrush inserted and the cover in another closed position;

FIG. 11 is a top front left side perspective view of FIG. 1 having an electric toothbrush head inserted and the cover in another closed position;

FIG. 12 is a view of FIG. 10 shown in use on a sink ledge for environmental context; and,

FIG. 13 is a view of FIG. 11 shown in use on a sink ledge for environmental context.

Broken lines are used to illustrate portions of the hygiene implements holder with shield and other broken lines illustrate environmental subject matter that form no part of the claimed design.

1 Claim, 13 Drawing Sheets
